US00D509291S

(12) **United States Design Patent** (10) Patent No.: **US D509,291 S**
Cunningham et al. (45) Date of Patent: **** Sep. 6, 2005**

(54) **HEATING ELEMENT**

(75) Inventors: **Ian Westad Cunningham**, Matthews, NC (US); **Craig Stephen Roberts**, Huntersville, NC (US)

(73) Assignee: **Irwin Industrial Tools Company**, Huntersville, NC (US)

(**) Term: **14 Years**

(21) Appl. No.: **29/190,293**

(22) Filed: **Sep. 18, 2003**

(51) LOC (8) Cl. **23-03**

(52) U.S. Cl. **D23/336**

(58) Field of Search D23/332, 335-339;
 126/92 A, 92 B, 92 AC, 9 A

(57) **CLAIM**

We claim the ornamental designs for a heating element, as shown and described.

DESCRIPTION

FIG. 1 is a perspective view showing a first embodiment of my new design for a heating element;

FIG. 2 is a front view showing my new design shown in FIG. 1;

FIG. 3 is a right side view showing my new design shown in FIG. 1 and wherein the left side view of my design is a minor image of the right side view of FIG. 3;

FIG. 4 is a rear view showing my new design shown in FIG. 1;

FIG. 5 is a top view of my design shown in FIG. 1;

FIG. 6 is a bottom view of my design shown in FIG. 1;

FIG. 7 is a perspective view showing a second embodiment of my new design for a heating element;

FIG. 8 is a front view showing my new design shown in FIG. 7;

FIG. 9 is a right side view showing my new design shown in FIG. 7 and wherein the left side view of my design is a minor image of the right side view of FIG. 9;

FIG. 10 is a rear view showing my new design shown in FIG. 7;

FIG. 11 is a top view of my design shown in FIG. 7; and,

FIG. 12 is a bottom view of my design shown in FIG. 7. The broken lines in FIGS. 1-4, 6-10, 12, and the screen patterns shown in FIGS. 1-4, 7-10, are for environmental purposes only and form no part of the claimed designs.
